UNITED STATES PATENT OFFICE.

JOSEPH EDWARD ROSS, OF WILSONBURG, WEST VIRGINIA.

NON-REFILLABLE BOTTLE.

1,119,192.

Specification of Letters Patent.

Patented Dec. 1, 1914.

Application filed March 16, 1914. Serial No. 825,006.

To all whom it may concern:

Be it known that I, JOSEPH EDWARD Ross, a citizen of the United States, residing at Wilsonburg, in the county of Harrison and State of West Virginia, have invented a new and useful Non-Refillable Bottle, of which the following is a specification.

This invention relates to non-refillable bottles.

10 The object of the present invention is to provide a bottle with a cap which is permanently attached thereto and which cap is provided with a flexible diaphragm which is drawn up within the cap after the bottle 15 has been filled and the means whereby the diaphragm is drawn up is then removed.

A further object is to provide a diaphragm rigidly secured to the top of a bottle and above which is permanently placed 20 a housing. A protecting plate is placed across the opening within the housing and renders the diaphragm inaccessible. Initially the diaphragm is in a lowered position, allowing a liquid to be placed within 25 the bottle. After the liquid has been inserted therein the diaphragm is drawn upwardly. The string by means of which the diaphragm is drawn upwardly is then forcibly torn therefrom, which prevents the further manipulation thereof. With the diaphragm in its raised position it will be practically impossible to refill the bottle after 30 the contents have been removed.

With the foregoing and other objects in view and among which, simplicity, and low cost of manufacture are aspired, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

45 In the drawings accompanying this specification and forming a part thereof, the preferable embodiment of my invention has been illustrated, in which:

Figure 1 is a view in elevation of my improved non-refillable bottle. Fig. 2 is a sectional view thereof. Fig. 3 is a detail view of the valve portion of the non-refillable bottle in which the diaphragm has been moved or drawn upwardly, the bottle having 50 been filled with a liquid and which allows the contents of the bottle to be emptied

therefrom and prevents the ingress of a liquid therein. Fig. 4 is a detail view in perspective of the bridging plate. Fig. 5 is a detail view in perspective of the elongated 60 flexible diaphragm.

Referring to the drawings in which similar reference numerals designate corresponding parts throughout the several views, 65 6 is the body portion of a bottle or other receptacle which is provided with the upstanding neck 7 around which extends an annular groove 8. The metallic cap 9 is provided with the annular rib 10 which fits within and interlocks with the groove 8. 70 The cap is provided with a second rib 11 adjacent its upper extremity and above which is placed the bridging plate 12. The upper portion of the cap is substantially frustoconical in outline so that after the bridging plate has been forced above the rib 11 it will be held rigidly in such position. The bridging plate as illustrated in Fig. 4 is provided with the upstanding and corrugated rim 13 which provides a plurality of passageways 80 through which the contents of the bottle may flow.

Prior to the permanent securing of the cap upon the neck of the bottle, a flexible diaphragm 14 is placed across the top of 85 the bottle neck and is sealed in such position by the cap which has the inwardly projecting portions 15 at these points. A flexible element 16 is secured to the lower extremity of the conical-like diaphragm and 90 allows the diaphragm to be drawn upwardly within the cap, as illustrated in Fig. 3. The flexible diaphragm is provided with the stiffened rim 17 and the conical-like flexible portion 18. The portion 18 is provided 95 with the aperture 19 extending therethrough and which allows a liquid to flow through the diaphragm when traveling in a direction from the base toward the apex of the conical portion. A counter relative 100 flow of a liquid with relation to the diaphragm will result in the conical portion of the diaphragm being folded down upon itself, thus closing the aperture 19 with which it is provided. The conical portion of the 105 diaphragm will be prevented from passing through the rim which would result in the inversion of the conical portion by reason of the stiffened rim and the elongated manner in which the diaphragm is formed.

110 The flexible element or string 16 is secured to the apex of the conical portion of

the flexible diaphragm and extends upwardly through one of the corrugations 13 of the bridging plate and is provided with a knob or other handle 20 secured to its 5 remote extremity. The bottle as thus described is filled with a liquid, it being noted that as the bottle is being assembled care is taken that the conical portion of the diaphragm will be positioned with the apex 10 in a depending manner. After the bottle has been filled the apex of the diaphragm is drawn upwardly above the rim 17 and the string is forcibly torn therefrom. With the conical shaped diaphragm in an upright position, the liquid contents of the bottle may be emptied therefrom. Should 15 however an attempt be made to refill the bottle, the diaphragm will collapse upon the rim and the resulting folds or layers 20 will result in the complete closure of the aperture 19 and thus effectually prevent the ingress of liquid.

Having thus fully described my invention, what I claim is:—

- 25 1. A non-refillable bottle comprising a receptacle, a flexible elongated tubular diaphragm extending across and depending within the opening within the receptacle, a housing protecting the diaphragm, and means for reversing the diaphragm from its depending position to allow basal apex flow of a liquid and prevent apex basal flow.
- 30 2. A non-refillable bottle comprising a receptacle, a flexible elongated tubular diaphragm extending across the opening and adapted to extend therein during the initial filling of the receptacle, a housing permanently connected to the receptacle and protecting the diaphragm, and means for 35 reversing the diaphragm from depending to upstanding position subsequent to the initial filling of the receptacle, to allow flow 40

of liquid in a basal apex direction and prevent flow of the liquid in the opposite direction.

3. A non-refillable bottle comprising a receptacle, a flexible elongated tubular diaphragm extending across the opening and adapted to extend therein during the initial filling of the receptacle, a housing permanently connected to the receptacle and protecting the diaphragm, and means for reversing the diaphragm from depending to upstanding position subsequent to the initial filling of the receptacle, to allow flow of liquid in a basal apex direction and prevent flow of the liquid in the opposite direction, said means being removable from the diaphragm subsequent to such reversal.

4. A non-refillable bottle comprising a receptacle, a flexible elongated tubular diaphragm extending across the opening and adapted to extend therein during the initial filling of the receptacle, a housing permanently connected to the receptacle and protecting the diaphragm, means for reversing the diaphragm from depending to upstanding position subsequent to the initial filling of the receptacle, to allow flow of liquid in a basal apex direction and prevent flow of the liquid in the opposite direction, and a bridging element extending across the housing and above the diaphragm, there being an outlet opening for outflowing liquid between said bridging element and the housing.

In testimony that I claim the foregoing as my own, I have hereto affixed my signature in the presence of two witnesses.

JOSEPH EDWARD ROSS.
